9125

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 14,892, dated March 18, 1884.

Application filed February 13, 1884. Term of patent 3½ years.

To all whom it may concern:

Be it known that I, SARAH JANE SHIELS, of the city, county, and State of New York, have invented and produced a new and original Design for a Pattern of Misses' Costumes, (numbered 9,125;) and I do hereby declare that the engraved prints accompanying this specification convey to any one accustomed to using paper patterns a clear understanding of how a garment made up by the pattern will appear.

The design shows a round skirt and an over-dress. The skirt exhibits a long panel at the left side and a wide drapery crossing the front from the right side to the panel, displaying 15 draping plaits in its side edges, and deepening nearly to the bottom of the skirt toward the right-side edge. The overdress displays

closely-fitted jacket-fronts, flaring from the throat over a shorter pointed vest displaying buttons all the way down, and a closely-fitted 20 basque-back displaying a full deep sash-drapery exhibiting a shirring at its center and deep loopings at its front and back edges, coat-sleeves, and a standing collar.

What I claim as my invention, and desire to 25 secure by Letters Patent, is—

The design for a miss's costume, as shown in the engraved prints accompanying this specification.

SARAH JANE SHIELS.
